CORRESPONDENCE FILING MECHANISM

Frank Lloyd Wassell, Westport, Conn., assignor to
Georgene Parkin Wassell, Westport, Conn.

Application February 12, 1954, Serial No. 409,996

1 Claim. (Cl. 129—16)

This invention relates to filing mechanisms and embodies, more specifically, an improved form of filing mechanism by means of which correspondence and the like may be maintained in filed condition and yet readily accessible at all times.

The invention relates more particularly to a rotary filing mechanism, such as illustrated in applicant's copending application Serial No. 223,593, filed April 28, 1951, now Patent No. 2,750,051, for "Multiple Rotary Card File," and it is an object of the present invention to provide a rotary filing mechanism by means of which correspondence and like material to be filed may be maintained in a properly filed condition and within a minimum of space, yet readily accessible and available for removal from or replacement into the filing mechanism.

In my copending application Serial No. 342,859, filed March 17, 1953, now Patent No. 2,790,443, there is described a rotatable file supporting mechanism having outer supporting elements disposed in a plane substantially lower than the plane in which inner file supporting elements are disposed in combination with frame structure can be carried by the frame supporting elements, the frame structure being provided with folded flexible elements that are suspended by the frames.

The present invention relates particularly to a filing mechanism of the general type described in the second of said copending applications and, more particularly, it provides an improved filing mechanism which possesses the advantages of greater versatility and easier operation than the mechanism of said last named application.

In order that the invention may be more fully understood, it will be described with reference to the accompanying drawings, wherein:

Figure 1 is a partial plan view of filing mechanism constructed in accordance with the present invention;

Figure 2 is a sectional view taken along the line 2—2 of Figure 1, and looking in the direction of the arrows;

Figure 3 is a sectional view taken on line 3—3 of Figure 1, and looking in the direction of the arrows;

Figure 4 is a view in perspective of the frame member of Figures 1, 2 and 3.

Referring to the above drawings and particularly to Figures 1 through 4, filing mechanism is illustrated as being provided in the form of the vertical non-rotatable shaft 20, which may be mounted in a suitable base (not shown). One or more supporting means may be provided in axially spaced relationship upon the shaft 20, each supporting means comprising upper and lower plates 21 and 22, respectively, which are rotatably mounted on the shaft by means of thrust bearing assemblies 23 and 24, respectively. The plates 21 and 22 are in turn reinforced at their outer peripheries by cylinder 25. Mounted upon plate 21 adjacent the outer periphery thereof is a supporting means comprising an annular channel 26 which is rectangular in cross section and which has an annular slit 27 in the top wall of the channel. Joined to the bottom of lower plate 22 there are a plurality of radially extending arms 28 which, at their outer extremity, support

2

a hand rail 29 which extends concentrically of shaft 20.

The foregoing structure thus provides a rotatable supporting means in the form of an annular channel. The structure may, if desired, be sectioned or compartmented by one or more radially extending partition plates (not shown).

In order that material to be filed may be effectively supported in a properly filed condition, a plurality of frames is provided, each being formed with a longitudinal arm 30 and a downwardly extending arm 31. Each of the arms 30 is provided at its extremity with a toe 32 which serves as an anchoring means and which is adapted to engage the annular channel 26 in locking relationship by insertion through slot 27. Correspondence or other

15 material to be filed, can be supported by means of flexible folded sheet material 33, this material being suspended from the longitudinal arms 30 and suitably secured thereto at 34 (as indicated in Figure 2). The bottom fold 35 of the material 33 thus serves as a saddle or pocket 20 within which the correspondence or other material can rest.

In the form of the invention illustrated in Figures 1 through 4, the sheet material 33 is not only secured at 28 to the longitudinal arms of adjacent frames, but is also secured to the downwardly extending arms 31 of adjacent frames, as indicated at 36.

25 Spaced slots 37 may be provided in the portions of the material 33 that are folded about the arms 30 and 31 in order that indicating tabs or other indicia 38 may 30 be secured therein, as illustrated in Figures 1 through 3.

By providing the shaft 20 with a plurality of independently rotatable supporting structures there may be provided a multiple tier rotary file on each tier of which there may be supported a plurality of flexible folded sheet 35 materials in the form of filing pockets in which filed material is readily accessible at all times.

Each tier of the file may be conveniently rotated by simply grasping the hand rail 29 and applying slight horizontal pressure thereto. Another feature of the file is 40 that the frames are quite securely locked in place and thus protected against accidental dislodgement but yet at the same time adjacent frames can be readily and easily removed from the file by simply lifting upwardly and outwardly.

It is observed that material filed within the pockets 45 is readily accessible from the side, and thus may be easily inspected, removed, or inserted. This permits a plurality of rotatable filing mechanisms to be mounted in superposed relationship upon a common shaft without impairing the accessibility above mentioned.

50 While the invention has been described with specific reference to the accompanying drawings, it is not to be limited save as defined in the appended claim.

I claim:

55 Filing mechanism comprising; a vertical shaft; a central turn table rotatably mounted on said shaft and including a radially extending horizontal plate in which is formed an annular slot concentric with said shaft, a plurality of arms each being characterized by a toe at one end of the arm; each toe being formed by a vertical shoulder extending downward from the upper side of the arm at the said end thereof to a termination vertically spaced down from the under side of the arm in an amount equal to the thickness of said plate, a horizontal shoulder projecting away from said termination, and a curved 60 shoulder meeting the under side of the arm at a juncture which is horizontally spaced from said vertical shoulder by an amount only slightly less than the width of said slot; said curved shoulder extending downward and away from said juncture as a circular arc to a point beneath said termination, and extending beyond the last-named point to taper towards the said horizontal shoulder; each

toe of an arm being inserted in said slot to have the horizontal shoulder thereof bear against the under side of said plate radially inward of said slot and to have the under side of the arm bear against the upper side of said plate radially outward of said slot, with the vertical shoulder and the upper part of the curved shoulder of the toe being in close-fitting relation to, respectively, the radially inward and outward margins of said slot; each arm being thereby supported as a cantilever to extend radially and horizontally of the turn table, and each arm being thereby locked with said slot to be nondetachable therefrom except by upward rotation of the arm through an arc which is substantially equal in angular value to the said circular arc of the curved shoulder; each arm being maintained in radial alignment on the turn table by the close-fitting relation between the two margins of the slot and, respectively, the vertical shoulder and the curved shoulder of the toe of the arm; and flexible sheet material suspended between adjacent arms to form individual filing pockets,

the said mechanism providing free radial access to said pockets, however angularly distributed, throughout a full revolution of said turn table.
